[57] CLAIM

The ornamental design for a prefabricated building, as shown and described.

DESCRIPTION

FIG. 1 is a first embodiment of a front elevational view of a prefabricated building;
FIG. 2 is a rear elevational view thereof;
FIG. 3 is a left side elevational view thereof;
FIG. 4 is a right side elevational view thereof; and
FIG. 5 is a top plan view thereof;
FIG. 6 is a second embodiment of a front elevational view thereof;
FIG. 7 is a rear elevational view thereof;
FIG. 8 is a left side elevational view thereof;
FIG. 9 is a right side elevational view thereof; and
FIG. 10 is a top plan view thereof;

FIG. 11 is a third embodiment of a front elevational view thereof;

FIG. 12 is a rear elevational view thereof;

FIG. 13 is a left side elevational view thereof;

FIG. 14 is a right side elevational view thereof; and

FIG. 15 is a top plan view thereof;

FIG. 16 is a fourth embodiment of a front elevational view thereof;

FIG. 17 is a rear elevational view thereof;

FIG. 18 is a left side elevational view thereof;

FIG. 19 is a right side elevational view thereof; and

FIG. 20 is a top plan view thereof;

FIG. 21 is a fifth embodiment of a front elevational view thereof;

FIG. 22 is a rear elevational view thereof;

FIG. 23 is a left side elevational view thereof;

FIG. 24 is a right side elevational view thereof; and

FIG. 25 is a top plan view thereof;

FIG. 26 is a sixth embodiment of a front elevational view thereof;

FIG. 27 is a rear elevational view thereof;

FIG. 28 is a left side elevational view thereof;

FIG. 29 is a right side elevational view thereof; and

FIG. 30 is a top plan view thereof;

FIG. 31 is a seventh embodiment of a front elevational view thereof;

FIG. 32 is a rear elevational view thereof;

FIG. 33 is a left side elevational view thereof;

FIG. 34 is a right side elevational view thereof; and

FIG. 35 is a top plan view thereof;

FIG. 36 is an eighth embodiment of a front elevational view thereof;

FIG. 37 is a rear elevational view thereof;

FIG. 38 is a left side elevational view thereof;

FIG. 39 is a right side elevational view thereof; and,

FIG. 40 is a top plan view thereof.

The broken lines are for illustrative purposes only and form no part of the claimed design.
